GUARD

Edward Bruns, Chicago, Ill.

Application February 18, 1938, Serial No. 191,229

2 Claims. (Cl. 51—272)

This invention relates to improvements in guards for machines which are adapted, in operation, to discharge particles, such as particles of grinding wheels, particles of metal or glass, and which particles may be driven into the eyes of the operator. The guard is applicable, with beneficial results, to art glass grinding and cutting machines, key making machines, jeweler's lathes and grinders and metal turning lathes and indeed to any machine which includes a high speed cutting or abrasive wheel or other means which, in operation, is apt to throw off particles and which particles are likely to be quite hot.

The object of the invention is to provide a transparent guard adapted to be held in a position between the point of removal of particles and the eyes of the operator.

In such machines there is usually provided a highly rotating operating wheel such as an abrasive wheel or circular saw and below the point of the wheel to which the operator applies the articles he is working on, there is provided a rest or base plate.

Such machines are usually of the "bench" type, that is, they are relatively small and are especially adapted to be secured upon a work bench, and as considerable of the work done upon such machines is of a very fine type especially in the manufacture of jewelry the operator is placed with his eyes rather close down toward the working point thus exposing them to the flying particles and especially such particles which may be driven down upon the rest plate and which rebound upwards towards the eyes of the operator.

As the transparent guard proper is made of glass, it acts as a reflector and it sometimes happens that a light is reflected into the eyes of the operator from the guard, this prevents the operator seeing clearly just what he is doing, and it is one important point of the invention that the guard is so mounted that it can be readily tipped slightly at least enough to avoid such reflection but not interfere with a clear view of the point of operation.

In operation upon metal articles made of the precious metals, without the guard, the particles rebound from the rest plate and are widely scattered, but with the use of the guard the particles are directed back upon the base plate where they accumulate and can be readily saved.

The invention will be more readily understood by reference to the accompanying drawing forming part of this specification and in which I have portrayed a grinding or abrasive wheel provided with a guard made in accordance with the

invention. It should be understood that such showing is typical merely of the application of the guard to the many different machines and situations where it will be of benefit.

The invention is more specifically set forth in the appended claims and it is to be clearly understood that the scope of the claims is not to be in any wise limited to the specific details of construction and application herein shown and described except where such specific limitations are incorporated in the claims.

In said drawing:

Fig. 1 is a side elevation of a grinding machine equipped with a guard in accordance with my invention;

Fig. 2 is a fragmentary, top plan view of the assembly shown in Fig. 1;

Fig. 3 is a fragmentary, top plan view of the guard proper; and

Fig. 4 is a fragmentary, sectional view on the lines 4—4 of Figs. 1 and 3.

The grinding machine shown in the drawing, as has been explained is typical of any suitable machine to which the guard may be applied and comprises a base or frame 10 adapted to be secured upon a work bench or table 11 and carries a horizontal rotatable shaft 12 in suitable bearings 13 and this shaft carries a grinding wheel 14 rotatably secured on the shaft. The shaft 12 may be rotated by any suitable means, not shown, and the grinding wheel 14 is rotated with the shaft, in the direction of the arrow on Fig. 1. A sheet metal guard 15 is usually provided which is upstanding from the base at the rear of the wheel 14 and is curved over the upper part thereof as best shown in Fig. 1. At the front or working side of the wheel there is usually provided a rest or base plate 16 arranged horizontally as shown and below the point 17 on the periphery of the wheel where the work 18 is applied to the wheel.

The guard of the invention designated generally by 19 comprises a glass plate which may be plate glass but is preferably what is known as unbreakable safety glass, and also though not necessarily a second sheet of glass 21 is arranged below and in flat contact with the plate 20 and these two plates are clamped tightly together by a clamping and guard mounting bolt structure 22 designated generally by 22.

The top plate 20 is provided with a hole 23 about midway between its ends and adjacent to one edge to receive the bolt structure 22, and the lower plate 21 is provided with a similar hole 55

24 registering with the hole 23 and for the same purpose.

The guard 19 is mounted in position by means of the bolt structure 22 upon the forward end 5 of the sheet metal guard 15 which is provided with a hole 25 for this purpose.

As shown in dotted lines 26—27 in Fig. 1, the particles thrown off by the wheel 14 strike the rest plate 16 and rebound upwardly. When the 10 guard 19 is in place the particles hit the underside of the lower plate 21 and are directed back to the rest plate but by this time their speed is so reduced that most of them accumulate on the rest plate 16. In such stoppage of the upward 15 moving particles the guard 19 performs its function of protecting the eyes of the operator which are usually positioned above the guard plate and in the line of travel of said particles.

The continual impingement of the particles on 20 the underside of the guard 19 tends to cut the said lower surface and finally to cloud it to such an extent that the glass has to be renewed. Instead of exposing the lower face of the main sheet 25 to the grinding action of the impinging particles, and which main sheet is more or less expensive, I protect its lower surface by the lower guard plate 21, which can be made of much less expensive glass and can be renewed when needed at small cost.

30 The bolt structure 22 by which the two sheets of the guard 19 are clamped together and by which the guard 19 is mounted on the sheet metal guard 15 includes a universal or ball joint so that the guard 19 can be readily tipped slightly 35 one way or the other as may be necessary.

In the use of such grinders it frequently happens that an illuminating lamp will be so positioned that the operator will see the reflection of the light in the guard 19 when operating the 40 grinder. It is obvious that when this condition arises a slight tipping of the guard 19 longitudinally will carry the light reflection off of the guard and eliminate this hindrance to good work.

The bolt or mounting assembly 22 comprises a 45 tubular member 28 which is exteriorly screw threaded to receive a clamping nut 29 on its upper end and a clamping nut 30 on its lower end. The tube 28 fits loosely in the holes 23 and 24 in the glass plates and I preferably arrange 50 slightly yielding washers 31 between the glass plates and said nuts to avoid possible breakage of the plates. The lower nut 30 is extended down in tubular form and is exteriorly screw threaded on its lower end 32 to receive a nut 55 member 33. The nut member 33 is provided at its lower side with an internal flange 34 which is formed at its inner edge to fit upon a ball-like member 35. Between the ball 35 and the lower end of the tube 28 I arrange a compression spring 60 36 and between the lower end of the spring 36 and the ball 35 I arrange a ring 37 which is formed on its lower side to fit upon the upper surface of said ball 35. By screwing the nut member 33 up 65 the ball 35 is clamped in place by a yielding pressure, due to the spring 36. The ball 35 is formed on the upper end of a stem-like member 38 and

which extends downwardly from the ball and its lower end is exteriorly screw threaded to receive a clamping nut 39 and the member 38 is provided with an external circumferential collar 40 above its lower end.

5 In mounting the guard 19 on the sheet metal guard 15, the lower end of the stem 38 is entered through the hole 25 in the guard 15 and is tightly clamped thereon by the nut 39. The universal or ball connection as described, allows the guard 10 19 to be tipped to suit the conditions and the friction on the ball 35 holds the guard 19 firmly in its adjusted position. At times it may be necessary to remove the guard 19 out of its operating position to permit certain forms of work 15 to be presented to the wheel 14. This is accomplished by swinging the guard 19 around through 180 degrees as shown in dotted lines in Figs. 1 and 2.

As the collar 40 is quite limited as to diameter 20 due to the necessity of its passing through the opening in the clamping nut 39, I preferably provide a metal washer 41 between the collar 39 and the guard 15 to increase the area of contact and to hold the guard 19 more firmly in position.

25 To protect the glass plates 20 and 21 from possible chipping or fracture by reason of contact in the holes 23 and 24 with the metallic connecting tube 28, I arrange a non-metallic tube 42 on the metal connecting tube 28. Preferably the tube 30 42, which is in the nature of a bushing, is made of some material such as rubber which is at least slightly yielding so as to avoid all strain on the glass at this point.

35 As many modifications of the invention will readily suggest themselves to one skilled in the art, I do not limit or confine the invention to the specific details of construction and operation herein shown and described except within the scope of the appended claims.

40 I claim:—

1. A device of the character described comprising a glass guard plate having a hole therethrough and a resilient bushing in said hole, and means for mounting said guard plate, said means comprising a bolt extending through said bushing, means on said bolt for clamping said guard plate thereon and permitting rotative adjustment of said guard plate about said bolt, said clamping means including resilient washers on said bolt 45 in contact with said guard plate, and means for attaching said bolt to a fixed support.

50 2. A device of the character described comprising a glass guard plate having a hole therethrough, a protective sheet of cheaper transparent material arranged below said plate and having a hole therethrough, and means for mounting said plate and said sheet in superposed relation, said means comprising a bolt extending through said holes, means for attaching said bolt 55 to a fixed support, and means adjacent the free end of said bolt for clamping said plate and said sheet removably together upon said bolt and permitting their rotative adjustment about said bolt.

65 EDWARD BRUNS.
